[57] **CLAIM**

The ornamental design for a snap tab mounting body for pleated drapery system, as shown and described.

DESCRIPTION

FIG. 1 is a perspective view of a snap tab mounting body for pleated drapery system, showing the new design;

FIG. 2 is a front elevational view of the snap tab mounting body for pleated drapery system of FIG. 1, on a somewhat reduced scale;

FIG. 3 is a right side elevation of the snap tab mounting body for pleated drapery system of FIG. 1, on a somewhat reduced scale, the left side elevation being a mirror image thereof; FIG. 4 is a rear elevational view of the snap tab mounting body for pleated drapery system of FIG. 1, on a somewhat reduced scale; and,

FIG. 5 is a bottom plan view of the snap tab mounting body for pleated drapery system of FIG. 1, on a somewhat reduced scale, the top plan being a mirror image thereof.

The broken line showing of a snap portion is for illustrative purposes only and forms no part of the claimed design.
